Primary Examiner — Darlington Ly

CLAIM

The ornamental design for a vehicle protective panel, as shown and described.

DESCRIPTION

FIG. 1 is a perspective view of the vehicle protective panel showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.
